UNITED STATES PATENT OFFICE

GLENN E. EDMUNDS, OF COLUMBUS, OHIO, ASSIGNOR TO THE BONNEY-FLOYD COMPANY, OF COLUMBUS, OHIO, A CORPORATION OF OHIO

REPLACEABLE EXCAVATOR TOOTH

Application filed January 29, 1930. Serial No. 424,369.

This invention relates to teeth for use on excavating implements, such, for instance, as power operated shovels, ditchers, skimmers, drag lines and cranes, in which, for motives of economy, it is usual to produce the tooth in separately formed point and base members, in order that the point member, one side of which in use wears away more rapidly than the other, may be replaced by a new point member. The invention has for an outstanding object to provide an improved form of connecting structure between the meeting ends of the separately formed point and base members, and particularly a form of connection which, while being very secure in its capacity to withstand stresses, will also be of such simple design as to make it very economical to produce by ordinary foundry practice and to be made from manganese steel or any other alloy steel suitable for the purposes to which the tooth is placed.

It has long been the practice in replaceable point teeth of this kind, to make them reversible, that is, to permit the point member to be changed in its operative position upon the base member after a certain degree of wear has taken place, in order to present an unworn surface with the end in view of securing longer effective use of such point members. Practice has also proved that it is not a real economy to reverse these point members after the first initial wear has taken place, for the reason that such a reversible point member is too dull to be used again until it has been resharpened, either by grinding or forging. Here again, the reversible tooth does not prove to be an economical factor because the user invariably leaves the point member in use as long as it will dig so that when it is eventually removed it is practically worn out. In other words there is not enough stock of metal left to grind or forge the point member to a sharp edge again. Therefore, the reversible tooth is generally used but once and if it is resharpened and used again it will have lost in length over substantially one half of its digging capacity, so that in reality such a reversible tooth becomes merely a short lived replaceable tooth.

The present invention is based upon a recognition of the short life of the ordinary reversible tooth and the foremost object thereof is to produce an improved replaceable tooth which will possess a much longer effective life in connection with excavating apparatus than teeth heretofore designed for this service. The design of my improved replaceable tooth lends itself toward a much stronger base portion or member as well as a superior tooth or point member design.

It is another object of the invention to construct the tooth so that the base member or shank which supports the replaceable point member comprises practically a solid nose extension and from which has been eliminated the structurally weak wings or jaws which cause so much trouble with the greater majority of reversible teeth. It is another object of the invention to extend the projecting nose at the front end of the base member under the replaceable point member and flush with the base member, thus making a strong support for the replaceable point.

The greatest wear on any tooth of this kind comes on the nose and the top surfaces of the tooth, so that in the reversible type both sides are equal in order to possess reversibility. As a result the first life of the tooth is cut short because such teeth are designed for reversing and not for long life. This destroys the practicability of such a reversible tooth for the reason that the user will not take time to change the teeth as often as they should be in order to get extended life from them. In other words, these teeth are worn out after their first application and even when resharpened they are still inefficient because they are too short to put back on the bucket lip.

The present invention provides a tooth which possesses a very great degree of mechanical strength, long life under hard conditions of service and yet one which may be readily replaced when desired on the working lip of an excavating device. In obtaining this end the nose of the replaceable tooth member comprising the present invention is provided with a forwardly disposed angular surface so designed as to be self sharpening.

while the tooth is being used. Further, this tooth will not only be heavier at its working edge or nose but can be very much longer, which provides for continued use after considerable wear has taken place.

It is a further object of the invention to provide an improved type of wedge lock between the replaceable point member and the base member, wherein the wedge consists of a tapered key which is driven into registering recesses provided in the base and point members to hold such latter members in secured relationship and to effectually prevent their accidental separation.

With these and other objects in view, which will appear as the description proceeds, the invention consists in the novel features of construction, combination of elements and arrangement of parts hereinafter to be more fully described and pointed out in the appended claims.

In the accompanying drawings:

Figure 1 is a top plan view of the improved tooth assembly comprising the present invention,

Figure 2 is a side elevation of the tooth, illustrating the bucket lip in vertical section.

Figure 3 is a vertical sectional view taken through the tooth.

Figure 4 is a horizontal sectional view on the plane indicated by the line 4—4 of Figure 3,

Figure 5 is a transverse vertical sectional view on the line 5—5 of Figure 3,

Figure 6 is a detail perspective view of the base member of the tooth,

Figure 7 is a similar view of the point member, and

Figure 8 is a detail vertical sectional view of a slightly modified form of the invention.

Similar characters of reference indicate corresponding parts throughout the several figures of the drawings.

My improved two-part tooth comprises a body or base member 1 and the removable or replaceable point member 2. The base member is recessed to form a pair of horizontally extending jaws or shanks 3 and 4, one of which, as for instance the lower, is usually longer than the other, and which jaws are bolted to the bucket lip or side by suitable bolts or other fasteners 5, the forward edge or lip 6 of the bucket fitting snugly in the recess 7 formed between the jaws 3 and 4. The lip engages the forward vertical wall 8 of said recess, so that thrusts on the tooth are imparted directly to the bucket lip and not through the medium of the bolts thereto.

The base member 1 is provided with a forwardly projecting nose portion 9 at its forward end which portion or extension is of less width than the main body of the base member 1 as shown in Figure 4, to provide lateral bearing surfaces or shoulders 10, which are arranged at an angle with respect

to the vertical. The point member 2 is formed, in turn, with a pocket 11 which receives the nose extension 9 and the walls of the pocket are shaped to conform with the walls of the extension 9 so that the latter will fit snugly and securely within said pocket. The insertion of the nose extension 9 into the pocket 11 is limited by the engagement of the shoulders or surfaces 10 with corresponding inclined shoulders or surfaces 12 provided on the point member 2, and which surfaces serve to receive the thrusts and stresses imparted from the point member to the base member.

The upper portion of the base member 1 is provided with a flat inclined surface 13 which forms a rearwardly extending continuation of the flat upper surface of the nose portion 9. The surface 13 terminates at its rear edge in an upwardly directed inclined shoulder 14 and, additionally, the surface 13 includes a transversely extending keyway 15. To the rear of the keyway the surface 13 is formed with a socket 16 which extends into the base member 1 to a position beyond the rear part of the shoulder 14.

The outer walls of the point member 2 lie substantially flush with the corresponding walls of the base member 1 so as to provide for flush adjoining surfaces. The rear portion of the point member 2 includes an upwardly and angularly extending integral ledge 17, the lower surface 18 of which engages with the inclined surface 13 of the base member and is coextensive with the surface 13. The surface 18 of the point member carries an integral shoulder lug 19, which is shaped to be received within the rectangular socket 16 formed in the surface 13. Also, the ledge 17 terminates at its rear end in the bevelled surface or shoulder 20, which engages firmly with the inclined surface or shoulder 14 of the base member 1.

To retain this interfitting relationship between the base and point members I preferably use a wedge key 21 which is driven into the keyway 15, particularly into engagement with the rear surface 22 of the lug 19 and the opposite wall of the keyway 15. The surface 22 conforms with the angularity of the key 21 so that as the latter is driven into its tight position firm frictional engagement is provided between the surfaces 10 and 12 and also the surfaces 14 and 20 of the base and point members respectively. The ends of the key 21 may be turned laterally to produce the wings 23, which engage with the countersunk portions of the base member 1 to lie flush with such sides and to prevent the accidental withdrawal of the key. By this construction a strong and substantial connection is provided between the separable tooth parts with the end in view of permitting the tooth to receive the severe strains and stresses of service without injury or breaking of parts, a feature

which is considered to be of far greater practical importance than the mere rendering of the point member reversible. It will be observed that the nose portion or forward portion of the base member underlies the greater portion of the length of the point member so that the digging strains are effectually absorbed. When the tooth member is moving upwardly in the action of scooping or digging, the lower wall 24 of the pocket 11 engages with the lower surface of the nose extension 9 to absorb the thrusts imparted to the top of the tooth member in the direction indicated by the arrow *b* in Figure 3. Similarly, these thrusts are absorbed also by the shoulder 14.

As shown in Figure 8, I may use in place of the wedge key 21 a bolt 25 for the purpose of connecting in detachable order the base and point members together. This construction may be employed in lieu of the key 21 as a constructional variation.

In addition to the connection between the point and base members an outstanding feature of the present invention resides in the construction of the point or digging tip of the tooth. This tip instead of coming to a point as is the case in earlier constructions, is extended to provide a metal shank of considerable thickness, as indicated at 26, and the shank is also of increased length over previous devices. The upper surface of the shank when viewed in side elevation is, as shown in Figure 3, of curved or arcuate form, as indicated at 27, while the lower surface of the shank is substantially flat, as at 28, and terminates short of the upper surface 27. The surfaces 27 and 28 are united by a downwardly and rearwardly inclined front wall 29, which is arranged at an angle of 40 or 45 degrees to the vertical in order to produce a sharp digging edge at the point of juncture of the walls 27 and 29, which is indicated by the numeral 30. In most digging or excavating operations, the shovel or scoop while moving in a digging path describes an arcuate course of movement in a generally upward direction and the inclination of the surface 29 is that which would be produced in any event by the wear on the nose portion of the tooth if the surface 29 were in practice formed straight or perpendicular to the horizontal.

By this construction of the digging point of the tooth it will be seen that the operation of the tooth will be efficient even if the metal wears practically back to the nose extension 9 and in fact the nose portion may be worn this much before replacement of the point members is necessitated.

To reduce the amount of wear which takes place on the digging tip of the tooth the surfaces 27 and 28 are provided with longitudinally extending grooves 31 which are formed to receive through welding an extremely

hard wear resisting metal alloy. The grooves 31 are filled with this alloy, which possesses a much greater degree of hardness than that from which it is practicable to form the point member 2, and due to the presence of the added alloy wear on the tooth member by reason of abrasion or other causes is resisted as greatly as is possible.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty adherent in my invention as broadly as possible in view of the prior art.

What I claim as new and desire to secure by Letters Patent is:

1. A tooth for excavating implements comprising separable base and point members, the point member being arranged in advance of the base member and provided with side walls arranged for registration with the corresponding walls of the base member, an integral nose extension of less width than the base member formed to project forwardly from the base member for reception within a correspondingly formed pocket provided in the rear portion of the point member, a ledge integrally formed with said point member and received within a recess provided in the upper surface of said base member, a lug integrally projecting from the lower surface of said ledge and received within a pocket formed in said base member immediately below but in communication with said recess, and removable securing means for retaining the nose extension on said base member and the lug on said point member in their respective pockets.

2. An excavator tooth comprising base and point members, said base member terminating at its forward end in an inclined planar surface, the ends of said surface terminating in longitudinally offset inclined shoulders, the forward of said shoulders being provided with a nose extension receivable within a pocket formed in said point member, a ledge formed upon the rear portion of said point member and positioned upon the inclined surface of the base member, a lug extension carried by the under and rear portion of said ledge and receivable within a pocket provided in said base member, and a locking key positioned in a keyway formed in said base member and arranged for engagement with said lug extension to maintain the rear portion of said point member in firm engagement with said offset shoulders.

In testimony whereof I affix my signature.
GLENN E. EDMUND.
